UNITED STATES PATENT OFFICE.

LEAMAN S. HARVEY, OF WATERBURY, CONNECTICUT.

LINE CLAMP.

Application filed October 14, 1927. Serial No. 226,106.

This invention relates to improvements in line clamps, and more particularly to a clamping device for adjustably connecting a pair of lines or cords, or the ends of a single line.

One object of this invention is to provide a fastener of the above nature which is adapted to be permanently connected to one end of a line and detachably connected to the other end of the line in such a way that the greater the tension in the line, the stronger will be the clamping effect of the fastener.

A further object is to provide a line clamp of the above nature which may be quickly and easily attached to and detached from the lines.

A further object is to provide a line clamping device of the above nature which is adapted to connect lines and cords of various diameters without injury to the material thereof.

A further object is to provide a line clamp of the above nature comprising a ball-holding casing having a tapered interior track for forcing the ball automatically into engagement with the line.

A further object is to provide a device of this nature which will be simple in construction, inexpensive to manufacture, easy to manipulate, compact, and very efficient and durable in use.

With these and other objects in view there have been illustrated on the accompanying drawings two forms in which the invention may be conveniently embodied in practice.

Fig. 1 represents a side view on a reduced scale of the first form of line clamp as it appears when connected to both ends of a clothes line.

Fig. 2 is a side view of the line clamp shown in Fig. 1.

Fig. 3 is a longitudinal sectional view of the same, showing in dotted lines the appearance of the cord when in clamped position.

Fig. 4 is a longitudinal sectional view of the same taken along the line 4-4 of Fig. 3, looking in the direction of the arrows.

Fig. 5 is a longitudinal sectional view, similar to Fig. 3, of a modified form of the invention.

Fig. 6 is a transverse sectional view of the same taken along the line 6-6 of Fig. 5, looking in the direction of the arrows.

Referring now to the drawings in which like reference numerals denote corresponding parts throughout the several views, the nu-

meral 10 indicates generally a hollow casing having at one end an elongated loop or eye 11 for permanent attachment to the knotted end 12 of a clothes line 13. As clearly shown in Fig. 1, the clothes line is adapted to pass around a pair of pulleys 14 and 15 secured upon any suitable supports, not shown.

The body member is provided with a pair of relatively wide parallel front and rear flat faces 16 and 17, and a pair of relatively narrow faces, said narrow faces comprising parallel forward portions 18 and 19 and converging rear portions 20 and 21.

In order to provide a track for a spherical ball member 22, the lower portion of the hollow interior of the body member 10 is made in the form of a channel 22^a of semi-circular cross-section, said channel being inclined forwardly and terminating in a constricted substantially circular opening 23, a swaged down lip 24 extending into said opening 23 for securely holding the ball in place.

The upper interior wall of the body member 10 comprises a horizontal semi-cylindrical channel member 25 which lies in alignment with the upper leg of the loop 11, whereby the free end 25^a of the clothes line 13 may be readily inserted into the constricted rear end 26 of the casing, said rear end 26 being circular in shape and of a diameter slightly less than that of the ball 22.

In operation, when it is desired to fasten the ends 12 and 25^a of the clothes line 13 together, the end 12 is first attached permanently to the loop 11 of the line clamp, as by knotting; and the free end 25^a is then inserted through the rear open end 26 of the casing until the free end 25^a passes out through the loop 11 and drops down to the position shown in Fig. 3. The operator will then grasp the casing 10 with one hand and pull rearwardly upon the line 13 with the other, at the same time pressing the ball 22 upwardly by inserting a finger through the opening 23, thereby causing the ball to frictionally engage the line. Continued rearward pulling upon the line will force the ball 22 to ride upwardly upon its track 22^a automatically until the line is securely clamped in position. By reason of the self-tightening action of the device, the greater the tension in the line, the stronger will be the clamping action of the ball.

In order to force the ball out of engagement with the cord 13 when the free end 25^a of the latter is pulled to the right, as viewed

on the drawing, provision is made of a curved downwardly inclined rib 27 extending forwardly across the front opening of the casing. The rib 27 serves two functions; first, to constrict the front end of the cavity in the interior of the casing and thereby prevent the escape of the ball 22 at that point; and second, to divert the ball 22 downwardly and forwardly away from the cord 25^a, as the latter is pulled forwardly with respect to the casing 10. It will be understood that the ball 22 will move in this manner irrespective of the effect of gravity.

In the modified form of the invention shown in Figs. 5 and 6 the line clamp disclosed is similar in all respects to the first form shown in Figs. 1 to 4 except in the shape of the channels in the interior of the casing. In this instance, the upper interior channel 28 is made of such size as to snugly fit the line to which the device is to be fastened and said upper channel is considerably smaller in diameter than the lower downwardly inclined ball-receiving channel 29. By means of this construction, a pair of shoulders or ribs 30 and 31 will be formed at the junction between the channels 28 and 29, whereby when the line is tightened the ball will be prevented from being forced too far into the material thereof, and thus avoiding possible injury thereto.

When it is desired to release the cord, it will only be necessary to pull forwardly upon the free end 12 of the cord, whereupon the ball will drop down to its original position.

While there have been disclosed in this specification two forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a line clamp, a hollow body member having an interior cavity converging toward one end, a ball member housed within said body member for frictionally clamping the free end of a line, and means extending from said body member for permanent attachment to the other end of the line, said body member having a side opening at its large end to permit the operator to insert his finger for pressing the ball member into engagement with said line.

2. In a line clamp, a hollow body member having an interior cavity converging toward one end, a ball member housed within said body member for frictionally clamping

the free end of a line, and means extending from said body member for permanent attachment to the other end of the line, the large end of said body member having an inwardly extending inclined rib to force 70 said ball member out of engagement with said line when the free end thereof is pulled.

3. In a line clamp, a hollow body member having an interior cavity converging toward one end, a ball member housed within 75 said body member for frictionally clamping the free end of a line, and means extending from said body member for permanent attachment to the other end of the line, said body member having a side opening at its 80 large end to permit the operator to insert his finger for pressing the ball member into engagement with said line, said body member having a laterally inclined interior rib for causing said ball member to move into 85 said side opening when the free end of the line is pulled.

4. In a line clamp, a hollow body member having an interior cavity converging toward one end, a ball member housed within 90 said body member for frictionally clamping the free end of a line, and means extending from said body member for permanent attachment to the other end of the line, said body member having a channel in its upper 95 interior face for receiving the line, and a ball-receiving channel in its lower interior face, said line-receiving channel being of a smaller radius than said ball-receiving channel, whereby said ball member will be prevented from cutting or otherwise injuring 100 said line.

5. In a line clamp, a hollow body member having an interior cavity converging toward one end, a ball member housed within 105 said body member for frictionally clamping the free end of a line, and means extending from said body member for permanent attachment to the other end of the line, said body member having a horizontal channel 110 in its upper interior face for receiving the line, and a downwardly inclined ball-receiving channel in its lower interior face, said line-receiving channel being of a smaller radius than said ball-receiving channel, whereby said ball member will be prevented from cutting or otherwise injuring 115 said line.

6. In a line clamp, a hollow body member, a spherical ball member located within said body member and freely movable therein, a 120 loop member extending from one end of said body member for permanent attachment to one end of the line, said ball member being adapted to detachably and frictionally clamp the free end of the line against said 125 body member.

In testimony whereof, I have affixed my signature to this specification.

LEAMAN S. HARVEY.
